(57) **CLAIM**

The ornamental design for a ergonomic handle for hand tool,
as shown and described.

DESCRIPTION

FIG. 1 is a perspective view of the invention viewing the tool
from the left front;

FIG. 2 is a perspective view of the invention viewing the tool
from the left rear;

FIG. 3 is a left side elevational view of the tool of the invention,
the right side being a mirror image of FIG. 3;

FIG. 4 is a bottom view of the tool of the invention;

FIG. 5 is a top view of the tool of the invention;

FIG. 6 is an elevational view of the front end of the tool of the
invention; and,

FIG. 7 is an elevational view of the rear end of the tool of the
invention.

The broken lines define areas of the design that are not
claimed.
